1

This invention relates to dispensing, and more particularly to methods and devices for dispensing viscous or semi-solid materials, such as heavy lubricants, under pressure.

The general object of the invention is to provide novel and improved apparatus and methods of the class described.

A more specific object of the invention is the provision of a force-feed pump for viscous or semi-solid lubricants and the like, in which novel and efficacious means are provided for insuring that an adequate charge of material from the reservoir or container is always available in the pump chamber.

In designing any compressor or injector for the dispensing of heavy lubricant under pressure, the same difficulty is encountered, namely, the proper feeding of the force pump.

Heavy lubricant, such as grease for automotive vehicles and other machinery, is a material which does not obey the laws of hydrostatics, since it is not sufficiently fluid to seek its own horizontal level, at least at normal temperatures. However, in order to insure its distribution or dispensing under pressure, it is necessary to introduce the charges promptly and efficiently into the chamber or cylinder of the force pump. In order to effect this purpose, the mere suction of a pump is generally insufficient and without some other means of feeding the pump, the distributor or injector device is quickly rendered inoperative.

Various proposals have been made, and have been used with indifferent success, for the purpose of effecting in some fashion the feeding or priming of the pump with these heavy lubricants. These measures have generally involved one of the following expedients: inclosing the lubricant in a sealed container into the interior of which compressed air is introduced; providing a gravity or power actuated piston within a cylindrical reservoir, which piston is adapted to rest mechanically upon the surface of the lubricant and cause the delivery of the same to the pump; providing an apparatus including rotating blades which are adapted to convey the lubricant to the pump in accordance with the principle of the worm conveyor.

These devices function effectively only in the case of feeding lubricants which have relatively little compactness. When used with lubricants of average or dense consistency they lead to frequent breakdowns. During operation, the manipulation of the force pump causes hollows or air pockets to form in the body of lubricant

2

and this completely disables the compressor, which can be started again only after a reduction or elimination of such pockets.

The present invention contemplates the provision of means for insuring the continuous packing of the lubricant and its introduction into the pump cylinder in continuous form without voids or air pockets. This purpose is accomplished by subjecting the reservoir or container which holds the supply of lubricant and which is provided in its lower portion with the force pump, to successive jarrings, the effect of which is to accumulate the lubricant in the lower part of the reservoir and thus feed it to the force pump.

15 The reservoir or container is carried on a vertical shaft, and at every pump stroke it is lifted to a certain height. When it reaches the highest point of its course, it is released and allowed to fall freely, acquiring acceleration until the instant when it strikes upon an abutment at the lowest point of its movement. At that instant, the reservoir itself stops abruptly, but the lubricant which it contains, because of the momentum developed during the fall, continues its movement after the stopping of the reservoir, and accumulates within the lowest part of the reservoir, which comprises the pump chamber, thus eliminating any voids or pockets.

20 In the preferred form of the invention, in order to combine the packing operation with the pumping procedure, the usual arrangement of the pump has been reversed and the piston thereof held stationary while the body or cylinder of the pump (which is integral with the reservoir or container) is movable. Thus in the reciprocal motion of the pumping arrangement two strokes are utilized, a forward stroke for the purpose of effecting the compression of the lubricant in the cylinder of the pump and its discharge therefrom, and the return stroke for the purpose of effecting the packing or cramping of the reservoir.

25 With this arrangement, if a stoppage should occur due to the formation of an air pocket, it is sufficient to continue the pumping movement for a few strokes, which will have the effect of eliminating the air pocket and packing the pump cylinder in a very positive manner. After a few idle strokes the pumping action will resume automatically and the flow of lubricant will proceed.

30 Another object of the invention is to provide both manually operable and mechanically operable means for a dispenser of this type.

35 A further object is to provide a mobile or portable device adapted to support and transport

a plurality of containers and pumping units, each adapted to dispense a different kind of lubricant ranging from motor oils to the heaviest greases; and to provide in such a portable dispenser, means for selectively bringing a given dispensing unit into operative position.

Other objects and features of novelty will be apparent from the following specification when read in connection with the accompanying drawings in which certain embodiments of the invention are illustrated by way of example.

In the drawings,

Figures 1, 2, and 3 are diagrams illustrating the principle of operation of the novel pump; Figure 1 showing the position of the pump prior to the beginning of the compression stroke; Figure 2 the position when the effective compression begins; and Figure 3 the position at the end compression stroke;

Figure 4 is a view in perspective of a quadruplex selective compressor-dispenser embodying the principles of the invention;

Figure 5 is a view in vertical section through the pump and supply cylinder or dispenser shown in Figure 4;

Figures 6 and 7 are fragmentary sectional views on an enlarged scale showing the pumping mechanism of the respective oil and grease pumps of Figure 5;

Figures 8, 9, and 10 are diagrammatic views showing several positions of operation of the dispenser elements; Figure 8 showing the positions of the pump cylinder, the elevating slide block, and the treadle at the end of the compression or discharge stroke (corresponding to the diagram in Figure 3); Figure 9 showing the positions of the parts at the end of the impact or jarring stroke (corresponding to the diagram in Figure 1); and Figure 10 the release position of the parts preparatory to rotating the support to bring in the cylinder and pump into operative position;

Figure 11 is a perspective view of a grease drum or cylinder which may be used in preparing a filling cartridge for the cylinders of the dispenser;

Figure 12 is a fragmentary sectional view of the lower portion of a grease cylinder showing novel means for stirring or whipping the lubricant to facilitate the packing thereof; and

Figures 13, 14, and 15 are somewhat diagrammatic views in vertical section and elevation, showing three successive positions of operation of a modification in which the device may be mechanically operated or power driven; Figure 13 showing the position of the operative parts at the beginning of the compression stroke; Figure 14 near the end of the compression stroke just before the beginning of the jarring or compacting stroke; Figure 15 showing the parts at the end of the jarring stroke.

Before describing certain preferred embodiments of the invention in detail, the broad principles of operation of the invention will be set forth in connection with the diagrammatic showings in Figures 1 to 3 of the drawings. In these diagrams the lubricant reservoir is indicated by the reference character *a* and it is filled with a supply of heavy semi-solid lubricant or other material to be dispensed which is indicated at *a'*. The reservoir is narrowed at its lower end to form a pump body *b* which provides a chamber within which the pump shaft or piston *c* is adapted to be received with a rather close clearance. The piston *c* is hollow having a central passage-

way *c'* through which the lubricant may be discharged and there is disposed within the lower end of the bore *c'* of the piston *c*, a ball valve *h* which is urged toward its seat at the mouth of the bore *c'* by means of the coil spring *h'*. Preferably the piston, the reservoir, and the pump cylinder are all disposed axially of the dispenser.

The piston *c* is fixed with relation to the device, and the reservoir or container *a* and the pump body *b* are adapted to be moved through the distance *d* which indicates the total length of stroke of the pump.

At the beginning of the compression stroke which is the position shown in Figure 1, the lubricant fills the chamber enclosed within the pump body *b*, and it will be noted that in this position the reservoir descends low enough so that the piston *c* will be withdrawn entirely from the pump body *b*, the lower end of the piston being at this instant opposite the converging or tapered side walls *c* of the reservoir, a narrow annular space *e'* being afforded around the end of the piston through which lubricant may move downwardly into the pump body *b*.

When by some manual or mechanical means, the reservoir or container *a* is lifted along its axis, the lower end of the piston *c* (guided as necessary by the conical walls *e*) completely stops up the opening into the pump cylinder *b*, all as indicated in Figure 2 of the drawings. From this point on, the lubricant which is enclosed within the pump cylinder begins to be compressed, and since it has no other outlet than the axial channel or bore *c'* of the piston, the descent of the piston into the body of the pump will cause the discharge through the bore of the piston of a quantity of the lubricant equal to the volume of material contained within the body of the pump, and with a pressure proportional to the force lifting the reservoir. The upper end of the tubular piston is of course connected with the piping or hose system of the distributor or dispenser.

When the reservoir arrives at the upper end of its course *d* (as indicated in Figure 3) the lifting force is suddenly removed, and then under the influence of the weight of the container (augmented by spring action if desired) the container falls vertically through the height *d* to the lowest point of its course.

During the dropping of the pump body and reservoir, the piston valve *h* closes the bore *c'* and thus a partial vacuum tends to be created within the pump cylinder, and by the time the falling reservoir and pump chamber has reached the point indicated in Figure 1, the piston *c* has left the pump chamber and lubricant is free to enter the chamber *b* through the annular clearance space *e'*. The lubricant begins to enter the pump chamber both under the action of the outside air pressure on the surface of the body of lubricant *a'* as well as under the influence of the kinetic energy stored up in the lubricant. The stopping of the free fall of the container is effected by impact on the fixed piece or anvil *f* which determines the lowest point of the course of movement of the pump and reservoir. Upon such impact, the inertia of the body of lubricant causes the pump chamber *b* to completely fill with a charge which is ejected during the next cycle of operation of the pump.

Having described broadly the principle of operation of the invention, certain practical embodiments will be set forth in considerable detail. For example, there is illustrated in Figure 4 of the

drawings a portable dispenser adapted to carry and supply lubricants of three different types. Of course, within the scope of the invention, any desired number of containers and associated pumping arrangements may be carried in a similar manner, but it is probable that such machines would be limited by practical considerations to about four containers and pumping arrangements. For the sake of illustration, a machine carrying three separate supplies of lubricant is shown in Figure 4. The cylindrical reservoirs are indicated by the reference numerals 10, and it will be seen that they are provided with downwardly convergent bottle-like lower portions 11, the necks of which are received in and normally supported by the enlarged portions 12 of the three-armed spider member 13 which is supported upon a central shaft the lowest end of which is received within the socket member 15 of the central carriage frame 16 the forward end of which is pivotally carried by the axle 17 supported by the two ground wheels 18. The carriage frame 16 extends rearwardly and downwardly as at 17 and terminates in a laterally extended stop lug 19 and may be provided at an intermediate portion with a caster 20.

The central supporting shaft 14 which is received within the socket 12, and which in Figure 4 is concealed by the surrounding cylinders 10, carries at its upper end the disk or hub frame 22 which is provided with a plurality of upwardly extending divergent spokes or supports 23 to the upper ends of which is secured the hand wheel or circular handle 25, by means of which the entire dispenser may be tilted and rolled upon the ground wheels 18 and thus the lubricant transported to points where it is needed. The wheel 25 also affords means for rotating the shaft 14, the spider 13, and the dispensing units 10, 11 for bringing selected ones of these units to dispensing positions as will be described.

The upper ends of the reservoir cylinders 10 are provided with the enveloping lids or closures 27, which are preferably cylindrical or dome shaped and through which the tubular dispensing shafts 30 extend.

The disk frame 22 is provided at intervals around its periphery with lugs 32 which are kerfed to provide means for receiving the shafts 30 and permitting them to be removed from the lugs when the cylinders or reservoirs 10 are applied to or removed from the carrier, all of which will be explained in further detail in connection with Figure 5 of the drawings.

Sets of jointed tubing or piping 35 are coupled as at 36 to the several hollow outlet shafts or pipes 30 and each of these sets of pipes is provided with a discharge coupling as indicated at 37, by means of which it may be applied to the grease connection of an automobile or the like. The carrier is provided with a foot treadle 40 which is operatively connected with a device indicated generally at 41 for operating the pump associated with the particular cylinder or container which is disposed directly above the mechanism 41. The details of these devices will be presently described.

Referring now more particularly to Figure 5 of the drawings, the following elements will be recognized from the brief descriptions given in connection with Figure 4: the reservoirs or containers 10 with their converging lower portions 11, the hollow enlarged portions 12 of the rotating spider 13, this spider being fixed to the centrally disposed vertical shaft 14 which is rotatably

5 mounted within the housing 15 forming a part of the carriage 16 supported by the axle 17 on the ground wheels 18. A split collar 15 retains the central shaft 14 in rotatable position upon the carriage 16. The rear portion 17 of the carriage is shown in Figure 5 along with the caster 20. At the upper end of the shaft 14 there is shown the disk or header 22 to which the hand ring 25 for manipulating the device is secured by means of the straps or spokes 23. These spokes are preferably provided with tongues 24 upon which the discharge hose or piping 35 may be supported.

Referring now to the specific details exhibited by Figure 5, there may be mentioned the bottom castings 50 of the reservoirs 10 which are recessed as at 51, which recess, together with the chamber 52 within the lower portion 11 of the containers, provides the pump chamber. The pumping arrangement in the left-hand cylinder 10 in Figure 5, and also shown on an enlarged scale in Figure 6, will first be described. This dispenser is adapted for use in connection with the distribution of a heavy oil. Axially of the cylinder or container 10 there is supported the hollow shaft 30 which passes through a central opening in the top of the dome-like cover 27 and is received within the kerf or slot 32 formed in the lug 32 of the upper disk 22. Threaded 20 upon the hollow shaft 30 interiorly of the cover 27 is a nut 54 and exteriorly of the cover a conical nut 55 is threaded, these two nuts serving to clamp between them the cover 27 and the upper and lower disks or washers 56 and 57. The conical portion 58 of the nut 55 is adapted to be received within a similarly shaped recess in the lower surface of the lug 32. The coupling 30 provides means for attaching the piping 35 to the upper end of the hollow shaft 30.

The lower end of the hollow delivery shaft 30 is provided with a piston member 60 which is adapted to be closely received within the portion 52 of the pump chamber. A ball valve 61 serves to close the small opening in the bottom of the piston 60, this valve being urged downwardly 45 toward its seat by means of a spring 62.

A guide block or pedestal 64 is seated upon the sloping lower walls 65 of the container 10 and is provided with an opening in its upper end to receive and guide the lower end of the shaft 30, and the pedestal is also provided with a recess 66 providing a spring seat for the lower end of the coil spring 68 which surrounds the shaft 30 and seats at its upper end against the nut 54.

55 In this way a telescoping container comprising the elements 10 and 27 is provided, said elements being urged apart by means of spring 68 to assume the positions of the various parts shown in Figure 5.

The operation of the dispenser will be explained in greater detail later on, but it will be sufficient to indicate here that when suitable lifting means is applied to the bottom casting 50 of the pump and reservoir assembly, the entire reservoir 10 will be raised within the cover 27 against the pressure of the spring 68 and the piston 60, in effect, will descend within the pump chamber 52 causing the oil or grease trapped therein to pass through the opening in the lower end of the piston, displacing the valve 61 and passing upwardly through the hollow bore of the shaft 30 and thus through the piping 35 to the point of discharge. When the container and pump have reached the uppermost point of their movement, the lifting means is released and the container 10 allowed

to drop, both under the action of gravity and the expansive force of the spring 68, so that the casting 50 strikes the enlarged portion 12 of the frame 13, which acts as an anvil, and the chamber 55 is thus filled with lubricant which passes from the main portion of the reservoir 10 through the clearances indicated at 69' around the lower edge of the piston 60.

The construction and operation of the grease dispenser illustrated at the right-hand side of Figure 5 of the drawings and upon enlarged scale in Figure 7, will now be described. The intermediate and upper portions of the reservoir and dispenser in this instance are identical with the corresponding parts of the one just described in connection with the left-hand side of the figure and similar reference numerals are employed in indicating the several parts. This embodiment of the invention differs from the one previously described only in the arrangement of the pump, piston, and cylinder at the base 11 of the container 10, and the mechanism is more particularly adapted for the discharge of lubricating grease under high pressure, the grease being discharged under pressures of from 10,000 to 12,000 pounds per square inch. In this embodiment the lower end of the hollow shaft 30 is comprised by an extension 30a having a narrow bore 30b terminating at its lower end in a fine opening 61a. The extremely narrow opening 61a is the practical equivalent of the ball valve 61 employed in the preceding embodiment. The diameter of the constriction 61a is large enough to permit the free passage of lubricant under the pressure applied thereto, but small enough to offer effective resistance to the return of the lubricant when the latter is only under the influence of atmospheric pressure.

In this embodiment a smaller supplemental pump body 70 is employed to form the pump chamber, and this element is seated within the recess 51 within the bottom casting 50 of the assembly. The upper end of the pump body or cup 70 is shouldered as at 71 and is surrounded by the flange ring 72 which may be threaded upon the cup 70. A flanged packing element 74 is clamped between the two members 70 and 72 and forms a seal against the piston shaft 30a when it descends into the pump chamber. The pressure spring 68 seats upon the member 72 and urges the pump body assembly downward. The vertical annular flange of the packing element 74, due to the pressure which prevails in the pump body 70, is applied very strongly to the piston and prevents any leakage of lubricant, the seal becoming more effective the higher the pressure. However, it is to be noted that a leak would not cause a loss of material but simply the return to the reservoir 10 of a portion of the lubricant contained in the pump body 70.

The means for raising the several containers and pump assembly and jarring the material into the pump chambers will now be described. Preferably formed integrally with the supporting frame 16 is the tubular guide portion 75 and within this guide there is disposed for vertical reciprocation the cylindrical slide block or lifting element 77. The guide portion 75 is disposed directly beneath the enlargement 12 of the rotatable spider 13 and the opening in the portion 12 is of the same size as that in the guide portion 75 and in registry therewith. The lifting block or sliding cylinder 77 is fitted at its other end to the marginal shouldered portion of the casting

50 comprising the lower end of the reservoir pump assembly.

The treadle 40 is pivoted as at 79 to a downwardly extending bracket portion 80 of the carriage frame 16 and the shorter arm 81 of the treadle is operatively connected with the lifting block 77 by means of the link 82, this link being pivotally connected to the lifting block by means of the wrist pin 83 and to the short arm 81 of the treadle by means of the pin 84.

The operation of the device will be readily understood from an inspection of Figures 4 to 10 inclusive of the drawings, the last three figures showing diagrammatically three different stages 15 of the pumping operation. The distributor hose 35 which is attached to the particular unit 10 which is disposed above the lifting block is connected to the point to which the lubricant is to be applied. Then the treadle 40 is depressed until it strikes the stop flange 19 on the rear end of the supporting frame. This disposes the principal operative elements in the positions shown in Figure 8 of the drawings in which the unit 10 is lifted by the lifting block 77 which contacts with 20 the bottom casting 50 thereof and is guided upwardly within the tubular portion 75 of the frame. During this movement any material within the pump chamber 70 will be forced through the constriction 61a and upwardly 25 through the hollow interior 30b of the central shaft 30, 30a, and thence outwardly through the piping 35.

Next the foot is released from the treadle 40 and the container and pump assembly 10, 11 allowed to fall freely under the influence of gravity and the urging of the spring 68. The bottom casting 50 of the assembly strikes the anvil enlargements 12 at the ends of the arms of the spider 13 and this has the effect of jarring the lubricant from the main reservoir into the pump chamber 70 through the adequate clearances allowed, as shown in Figure 7. Thus any air pockets or voids which may be within the pump chamber will fill up and the pump is ready for 30 the next ejecting action which is effected, of course, by again depressing the treadle 40. The dropping movement of the various parts is indicated clearly in the diagram in Figure 9.

In order to bring any of the other tanks or 35 reservoirs 10 into position for dispensing the contents thereof, the shaft 14, along with the spider 13 and the upper disk frame 22, is rotated until the selected tank and pump unit is disposed above the plunger or lifting block guide 75. 40 However, in order to effect this rotatable adjustment, the lifting plunger 77 must be depressed sufficiently to be retracted well within the upper margin of the guide casting 75 and below the perforated anvil block 12. To accomplish this 45 the treadle 40 is raised to the extreme upper position shown in Figure 10 of the drawings, whereupon the lifting block or plunger 77 is withdrawn so that the spider 13 may be freely rotated to bring another unit into position above 50 the ejecting mechanism 75, 77.

In Figure 11 of the drawings there is shown a package adapted to be filled with semi-solid lubricant in order to provide a cartridge for charging the reservoirs 10. These containers comprise 55 essentially cylindrical drums 90 having top and bottom covers or closures 91 and 92. The drums are of slightly less diameter than the inside diameter of the reservoirs and in order to charge the reservoirs, the lids or covers 91 and 92 are removed from the cartridge and the cylindrical

portion of the drum 90 with its contained lubricant supply is introduced into the reservoir. In order to effect this operation, the dome-like covers 27 of the reservoir together with the central pump shaft 30 is depressed against the resiliency of the spring 68, the pump shaft 30 descending into the pump chamber and the conical nut 55 freed from the similarly shaped recess 58 in the lugs 32 of the upper bracket 22, and thus the upper ends of the shafts 30 may be withdrawn through the slots or kerfs 32' in the lugs 32. The entire container and pump unit is thus tilted about the supporting enlargements 12 at the ends of the arms of the spider 13 and may be then lifted out of the carrier for replenishing. The covers 27 are removed together with the pump shaft and spring 68 and the grease cartridge inserted, whereupon the mechanism is reassembled by reversing the procedure just described.

In Figure 12 of the drawings there is illustrated a modification of the invention in which there are provided spiral coil springs arranged in inverted conical configuration as shown at 95. These springs are secured to the central pump shaft 30 by means of the tight windings 96 at the apices of the spring devices. As in the other embodiments the lower end of the pump shaft 30 is adapted to enter and be withdrawn from the pump chamber 70, the sealing being provided by the flanged packing element 74 which is clamped to the upper edge of the pump body 10 by means of the threaded and funnel shaped annular flanged element 72'. This arrangement may well be used when very compact lubricants are dispensed. The larger convolutions of each spiral are adapted to rest against abutments extending inwardly from the walls of the reservoir 10 and exemplified by the pins or hooks 98. During the ascent and descent of the reservoir the springs will be deformed by alternate stretching and compression and this has the result of whipping the lubricant upon every pump stroke and thus modifying the consistency thereof and rendering the packing easier. The arrangement shown in Figure 12 may of course be applied to any of the embodiments illustrated.

The principles of the invention may be applied to a compressor or dispenser having mechanical or power driven control just as well as in the case of the manually operated device. One example of a mechanically driven dispenser is shown diagrammatically in Figures 13, 14, and 15 of the drawings. For purposes of illustration, the device is carried by a vertical shaft 100 secured to a wall or other fixed support 101 by means of the fastening elements 102. Fixed upon the vertical shaft 100 are the three bracket arms 103, 104, and 105. The bracket 104 carries the perforated anvil enlargement 112 upon which the lower end 111 of the reservoir 110 rests, the lower portion 111 containing the pump chamber 172. The cover 127 carries the pump shaft 130 just as in the case of the other embodiments, the assembly 110, 127 being urged apart by means of the coil spring 168. The upper or discharge end of the hollow shaft 130 is received within the kerfed end 132 of the bracket 103, a conical or spherical nut 155 being received within a similarly shaped recess on the bottom of the bracket enlargement or lug 132, this arrangement being exactly analogous to the others previously described.

The vertically reciprocating cross-head or 75

plunger 177 is guided in the hollow interior of the anvil abutment 112 and is driven by the following mechanism. Rotatably mounted upon a shaft 200 carried by the lower bracket 105, is a crank disk 201 which may be driven in the direction indicated by the arrows, by any suitable driving means. A crank arm 205 is also carried by the shaft 200 and the end 206 of the crank arm 205 is pivotally connected with the sliding 10 plunger 177 by means of the link 182. The crank arm 205 and the shaft 200 are freely rotatable upon the bracket 105 and the crank 205 is disposed alongside the face of the drive disk 201. The disk 201 is provided with a drive pin 210 15 which is adapted to abut the rearwardly extending portion of the crank arm 205 and to drive the crank as the disk moves in the direction of the arrows. The disk may be driven from an independent motor or from a rotating part on the machine to be lubricated.

In Figure 13 of the drawings the parts are in the position which they assume at the beginning of the compression or ejection stroke. The disk 201 is rotating at a relatively slow rate of speed 25 and the pin or abutment 210 moves the crank arm 205 in a clock-wise direction. Thus the lifting cross-head 177 is moved upwardly through the intermediary of the connecting link 182 and the container and pump assembly 110, 111 is raised.

In Figure 14 the parts are shown at the end of the compression or discharge stroke, the abutment 210 having moved the crank 205, 206 to the upper dead center position. Further movement beyond this point frees the crank from the driving abutment 210 and the weight of the pump and tank assembly augmented by the pressure of the spring 168 causes the assembly to drop to the position shown in Figure 15 whereupon the bottom of the tank 111 strikes the anvil portion 112 and the material is jarred and packed into the pump chamber 172. At this lower dead center position the parts remain at rest as shown in Figure 15 until the abutment 110 arrives in the upper position whereupon it again contacts the arm 205 and drives the crank as shown in Figure 13.

By this means, an even slow ascent of the reservoir is attained whereby a steady flow of material is dispensed through the upper end of the hollow shaft 130, and an abrupt and sudden descent of the tank is provided for, in order to jar the lubricant into the pump cylinder.

It is clear that the pedal operated apparatus shown in Figures 4 and 5 may be constructed with a single reservoir instead of the plurality as shown. In that case the outlet tube for lubricant which is attached to the upper end of the hollow piston rod 30 may be connected with a storage chamber for lubricant under pressure which may be located on the inside of the tubular upright shaft 14. Such a storage chamber may be composed essentially of the cylindrical hollow shaft containing the body of lubricant subjected to the pressure of a piston which compresses a very powerful opposing spring. The storage chamber will of course be provided with a check valve preventing the return of lubricant from the chamber to the reservoir and pumping arrangement 40, 41. An outlet tube from the storage chamber will of course be provided with a valve controlled by hand. Thus if the pedal 40 is manipulated several times in succession, a supply of lubricant under pressure will be accumulated in the storage chamber, against the pressure of

the spring pressed piston. Then the accumulated lubricant in the storage chamber may be distributed by the simple manipulation of the manually operated valve, without the constant actuation of the treadle 40.

Various changes and modifications may be made in the embodiments illustrated and described herein without departing from the scope of the invention as defined by the following claims.

Having thus described the invention, what is claimed as new and desired to be secured by Letters Patent is:

1. In a dispenser for semi-solid materials, such as heavy viscous lubricants and the like, a supporting frame, a reservoir mounted for vertical reciprocation in said frame, the narrowed lower portion of the reservoir constituting the chamber of a reciprocating force pump, a hollow tubular piston fixed relatively to said frame and adapted for relative motion within said reservoir and chamber alternately to compress and eject the contents of said chamber and to withdraw from the latter to permit recharging of the chamber, an outlet opening affording communication between said chamber and the interior of the hollow tubular piston, means for intermittently and alternately lifting said reservoir to eject the contents of the chamber through the hollow piston and letting the reservoir drop upon an abutment on said frame, whereby the lubricant is packed into the pump chamber without voids or cavities, and means connecting said tubular piston to a discharge point.

2. In a dispenser for semi-solid materials, such as heavy viscous lubricants and the like, a supporting frame, a reservoir mounted for vertical reciprocation in the frame, said reservoir being provided with a cup-like bottom extension of less diameter than the upper main portion thereof, said extension comprising a reciprocating-pump chamber, a hollow piston member attached at its upper end to said frame, and extending downwardly through the reservoir, the lower end of said piston member being of a diameter to fit snugly within said pump chamber, a one-way opening in the lower end of said hollow piston member, means for vertically reciprocating said reservoir with respect to the piston member so that at the lowermost point in the downward stroke the lower end of the piston member is withdrawn from the pump chamber and is disposed within the main portion of the reservoir, leaving an annular opening for the passage of lubricant from the main portion of the reservoir into the chamber, and whereby during the upward stroke of the reservoir the piston enters the pump chamber and forces the lubricant therein through the one-way opening and through the passageway in the hollow piston, discharge means connected with the upper end of said hollow piston, and means for abruptly terminating the downward stroke of the reservoir, whereby the impact jars the lubricant into the pump chamber and compacts it therein eliminating voids and cavities.

3. In a dispenser for semi-solid materials, such as heavy viscous lubricants and the like, a reservoir, a force pump having its pump chamber in the lowermost portion of said reservoir, a charging cartridge for supplying lubricant to said reservoir, said cartridge comprising a container with side walls of approximately the same size and shape as the side walls of said reservoir but having its bottom wall removed when inserted in

the reservoir, means for intermittently raising and lowering said reservoir and means for abruptly terminating the lowering stroke, whereby the mass of lubricant is jarred and continually urged downwardly and fed from said cartridge container and from the upper portion of the reservoir into said pump chamber without the formation of voids or cavities.

4. In a dispenser for semi-solid materials, such as heavy viscous lubricants and the like, a supporting frame, a reservoir mounted for vertical reciprocation in said frame, an abutment carried by said supporting frame itself entirely exteriorly of said reservoir, the lower portion of the reservoir constituting the chamber of a reciprocating force pump, a piston fixed relatively to said frame and adapted for relative motion within said reservoir and chamber alternately to compress and eject the contents of said chamber and to withdraw from the latter to permit recharging of the chamber from the reservoir, means for intermittently and alternately lifting said reservoir to eject the contents of the chamber and letting the reservoir drop upon said abutment, whereby the jarring serves to pack the lubricant into the pump chamber without voids or cavities, and a coil spring connecting the piston and reservoir and serving to urge the reservoir toward its downward position, thus supplementing the force of gravity in effecting the jarring stroke, whereby the speed and kinetic energy of the lubricant is increased.

5. In a dispenser for semi-solid materials, such as heavy viscous lubricants and the like, a supporting frame, a reservoir mounted for vertical reciprocation in said frame, the lower portion of the reservoir constituting the chamber of a reciprocating force pump, a piston supported by said frame and adapted for relative motion within said reservoir and chamber alternately to compress and eject the contents of said chamber and to withdraw from the latter to permit recharging of the chamber, means for intermittently and alternately lifting said reservoir to eject the contents of the chamber and letting the reservoir drop upon an abutment on said frame, whereby the lubricant is packed into the pump chamber without voids or cavities, and one or more coil springs of a helical configuration conforming to the nappe of a cone disposed within the reservoir, one terminal of the spring being secured to the piston and the other to the reservoir, whereby during reciprocation of the reservoir the spring will alternately contract and expand to agitate the lubricant and thus assist in eliminating such voids.

6. In a dispenser for heavy lubricants and the like, a supporting frame, a reservoir mounted for vertical reciprocation in said frame, the lower portion of the reservoir constituting the chamber of a reciprocating force pump, a piston fixed relatively to said frame and adapted for relative motion within said reservoir and chamber alternately to compress and eject the contents of said chamber and to withdraw from the latter to permit recharging of the chamber, means for intermittently and alternately lifting said reservoir to eject the contents of the chamber and letting the reservoir drop upon an abutment on said frame, whereby the lubricant is packed into the pump chamber without voids or cavities, said last named means comprising a plunger guided in said frame beneath said abutment, a pitman operatively connected with said plunger, an actuating means for said pitman operable to raise said

plunger during the pumping stroke and adapted to be released to permit the plunger and reservoir to fall during the return stroke.

7. The dispensing device as set forth in claim 6 in which said actuating means comprises a foot lever fulcrumed on said frame, and means pivotally connecting said pitman with said foot lever.

8. The dispensing device as set forth in claim 6, in which said actuating means comprises a crank member, a rotary follower adapted to push said crank member through substantially one-half revolution corresponding to the upward pumping stroke of the plunger and reservoir, and to allow said crank member to break contact with said follower during the one-half revolution corresponding to the free fall of the plunger and reservoir, and driving means for said follower.

9. The dispensing device as set forth in claim 6, in which said actuating means comprises a crank member, a rotary disk disposed adjacent the crank member and in a close parallel plane, a projection on said disk adapted to push said crank member through substantially a half revolution corresponding to the upward pumping stroke of the plunger and reservoir, and to allow said crank member to break contact with said projection during the half revolution corresponding to the free fall of the plunger and reservoir, and driving means for said disk.

10. A portable dispenser for heavy lubricants and the like, comprising a wheeled frame, a rotary carrier adjustable about a vertical axis on said frame, a plurality of reservoir and dispensing pump units mounted on said carrier, each having its pump portion in the lower part thereof, a lifting device at a fixed point on said frame, said carrier adapted to be rotated to position a selected one of said units in adjacent operative position relative to said lifting device, and means for actuating said lifting device to raise said unit and let it fall upon an abutment to jar the contents into compact condition in the pump.

11. A portable dispenser for heavy lubricants and the like, comprising a wheeled frame, a rotary carrier adjustable about a vertical axis on said frame, a plurality of reservoir and dispensing pump units mounted on said carrier, each having its pump portion in the lower part thereof, an abutment on the carrier, a lifting device at a fixed point on said frame beneath said carrier, said carrier adapted to be rotated to position a selected one of said units directly above said lifting device, and means for actuating said lifting device to raise said unit and let it fall upon said abutment to jar the contents into compact condition in the pump.

12. The dispenser as set forth in claim 10 in which the units are removably mounted on the carrier, the latter comprising a lower socketed member and an upper socketed member, the bottoms of said units being tiltably disposed in the sockets in the lower member and upper yieldable portions of said units, received in the units of the upper member.

13. The dispenser as set forth in claim 10 in which the units are provided with cover members, and with springs urging said cover members upwardly with respect to the reservoir portions of said units, and are removably mounted on the carrier, the latter comprising a lower socketed member and an upper socketed member, the bottoms of said units being tiltably disposed in the sockets in the lower member and the spring pressed cover members of the units being yield-

ably received in the sockets of the upper members of the carrier.

14. In a dispenser for heavy lubricants and the like, a supporting frame, a reservoir mounted for vertical reciprocation in said frame, the lower portion of the reservoir constituting the chamber of a reciprocating force pump, a piston fixed relatively to said frame and adapted for relative motion within said reservoir and chamber alternately to compress and eject the contents of said chamber and to withdraw from the latter to permit recharging of the chamber, means for intermittently and alternately lifting said reservoir to eject the contents of the chamber and letting the reservoir drop upon an abutment on said frame, whereby the lubricant is packed into the pump chamber without voids or cavities, said last named means comprising a plunger guided in said frame beneath said abutment, and actuating means for said plunger comprising driving means for operatively engaging the plunger and raising it during the ejecting stroke and automatically disengaging at the end of said stroke to permit the plunger and reservoir to fall freely upon said abutment during the return stroke.

15. In a dispenser for semi-solid materials, such as heavy viscous lubricants and the like, a supporting frame, a reservoir mounted for vertical reciprocation in said frame, a reciprocating force pump having its chamber at the lower portion of said reservoir and adapted to communicate therewith, a piston supported for relative movement with respect to said reservoir and within said chamber alternately to compress and eject the contents of said chamber and to withdraw from the latter to permit recharging of the chamber from the reservoir, means for intermittently and alternately lifting said reservoir during the ejection of the contents of the chamber by the piston and letting the reservoir drop upon said abutment whereby the jarring serves to pack the material into the pump chamber without voids or cavities, and spring means continually urging said reservoir downwardly toward said abutment, thus supplementing the force of gravity in effecting the jarring stroke, whereby the speed and kinetic energy of the lubricant is increased.

16. In a dispenser for semi-solid materials, such as lubricating greases and the like, a support, a reservoir having an imperforate bottom wall and being movable with respect to said support, an ejector pump chamber in the lower part of the reservoir, an anvil carried by said support beneath and exteriorly of said reservoir, means for raising said reservoir during the ejection action of said pump and for letting the reservoir drop from such raised position so that its bottom wall strikes said anvil, whereby the resulting jarring serves to pack the material into the pump chamber without voids or cavities, and without any discharge through the bottom of the reservoir.

17. In a dispenser for semi-solid materials, such as lubricating greases and the like, a support, a reservoir mounted for vertical reciprocation in said support, a reciprocating ejector pump having its pump chamber in the lower part of said reservoir, a hollow piston carried by said support and adapted for relative motion within said reservoir and said chamber alternately to compress and eject contents of the chamber and to withdraw from the latter to permit recharging of the chamber, an outlet opening affording communication between the chamber and said hollow piston, means for intermittently and alternately

75 piston, means for intermittently and alternately

lifting said reservoir to eject the contents of the chamber and letting the reservoir drop upon an abutment on the frame, whereby the lubricant is packed into the pump chamber without voids or cavities, and means connecting said hollow piston to a discharge point.

HENRI H. CHINCHOLE.
